(57) **CLAIM**

The ornamental design for an electric still camera, as shown and described.

DESCRIPTION

FIG. 1 is a top, front and side perspective view of an electric still camera showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof from the left of FIG. 2;

FIG. 7 is a side elevational view thereof from the right of FIG. 2; and,

FIG. 8 is a view similar to FIG. 1 but showing the parts in a different position.
